Primary Examiner — Doris Clark(74) *Attorney, Agent, or Firm* — Dunlap Bennett & Ludwig, PLLC; Anna Kinney(57) **CLAIM**

The ornamental design for a floor tile, as shown and described.

DESCRIPTION

FIG. 1 is a top front perspective view of a floor tile;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof; and,

FIG. 8 is an enlarged detail view taken along line 8-8 in FIG. 1.

The broken lines shown in the drawings depict a portions of a floor tile that forms no part of the claimed invention.
